(57) CLAIM

What is claimed is the ornamental design for a silverware caddy, as shown and described.

DESCRIPTION

FIG. 1 is a perspective view of a silverware caddy showing a new design;

FIG. 2 is a front view of the silverware caddy of FIG. 1;

FIG. 3 is a rear view of the silverware caddy of FIG. 1;

FIG. 4 is a left side view of the silverware caddy of FIG. 1;

FIG. 5 is a right side view of the silverware caddy of FIG. 1;

FIG. 6 is a top view of the silverware caddy of FIG. 1;

FIG. 7 is an exploded view of the unclaimed bottom surface of the silverware caddy of FIG. 1; and,

FIG. 8 is a bottom view of the silverware caddy of FIG. 1.

The components of the display shown in broken lines illustrate portions of the silverware caddy which form no part of the claimed design. Further, the vertical and diagonal broken lines are not meant to be indicative of any specified colors.
